[57] ABSTRACT

An impeller for a paper pulp having a plurality of blade receiving stations each receiving a blade with a bulbous end seated in an axial recess for locking the blade in position with the blade additionally being held by a slotted rotor and being bolted in place with its outer end shaped for refining.

REPLACEABLE VANE INSERT FOR IMPELLER

BACKGROUND OF THE INVENTION

In a paper stock pulping operation the rotors are run at a high speed and having cutting blades or vanes which engage the pulp and perform the pulping operation. One type of pulper is used on wastepaper refining. As these impellers operate, the vanes become dull and need regrinding to the required shape. In one form of construction, the vanes are integral with the rotor and this required removal of the full impeller to build up the leading surfaces of the impeller vanes with weld material and to grind the vanes to the required shape.

The impellers of a pulper of the type with which the present invention is employed operate continuously and provide positive high intensity mixing for the liquids in the pulper tank. An optimum impeller functions to assure good circulation and rapid pulp breakup. At relatively high impeller rotating tip speed, fast operation with more difficult pulps can be accomplished. Yet, this construction provides more stringent operating additions for the impeller vanes.

While certain features of the invention may be embodied in other types of structures, the structure is particularly well suited to use in a wastepaper pulper and will be described in connection with that use. The pulping of wastepapers is a large part of the paper industry, and over 90 percent of collected wastepaper is used in this way. Old newspapers, wrapping papers, boxes and other mixed papers are mechanically disintegrated at a high temperature until the wastepaper has been reduced to the desired degree of fineness, and the defibered stock is then used directly in making paperboard after a small degree of refining. The consistency of the wastepaper and the foreign particles make wear of the pulper and its pulping blades imminent and with wear it is essential that the leading surfaces of the impeller be repaired. The source of foreign elements in the wastepapers is obvious from their source which consists of mixed paper, kraft wrapping, old corrugated containers collected from industrial concerns, department stores and so forth, old newspapers and magazines, waste from printers, envelope manufacturers and manufacturers of special paper products, and cuttings from corrugated box and bag manufacturers. Because of the economy of using wastepaper, it is highly desirable that this source of pulp be employed to the largest extent possible. The wastepaper stock is processed on cylinder machine mills and in the absence of sufficient economical waste, they are forced to use higher and higher proportions of virgin pulp. It is thus highly desirable to provide an improved structure for the processing of wastepaper to bring down the cost and make the processing of waste more efficient and more desirable.

It is accordingly an object of the present invention to provide a unique refiner impeller wherein the impeller has vanes which operate integrally but wherein the vanes are removable for replacement or reconstruction.

A still further object of the invention is to provide an improved impeller having removable vanes which are held in place by a unique construction that positively positions them and holds them completely rigid, but which permits individual removal of the vanes for replacement when they are worn or for substitution of vanes of a different character.

Other objects and advantages of the invention will become more apparent with the teaching of the principles thereof in connection with the disclosure of the specification, claims and drawings, in which:

IN THE DRAWINGS

FIG. 1 is a fragmentary elevational view of an impeller rotor constructed in accordance with the principles of the present invention;

FIG. 2 is a fragmentary sectional view taken substantially along line II-II of FIG. 1; and

FIG. 3 is a fragmentary elevational view taken from the opposite side of the rotor as compared with FIG. 1.

DESCRIPTION OF THE PREFERRED EMBODIMENTS

An impeller 10 is cast in one piece and has an outer flange 10a, an inner flange 10b with a rim portion 10e therebetween and has strengthening webs such as 10c and 10d. The cast ring is arranged to be suitably attached such as by bolts received in threaded bosses 10f to a center portion of the rotor for being mounted in the refiner. The refiner will have a suitable housing, and in refiners such as used in wastepaper pulping, suitable inlets for the wastepaper and liquid and a discharge for the pulp will be provided.

The impeller rotor 10 is provided with a plurality of blade receiving stations such as 11 and 12, FIG. 3. At each station is secured a blade or vane 13 which is positioned on the rotor as an insert. The outer end 13a is shaped and ground for the refining operation.

The inner end of the vane 13 is held in place with a key-like lock including a bulbous insert 14. The insert fits a cylindrically shaped recess or socket 15 which is formed to extend axially into the impeller. The socket 15 is accurately positioned so that the bulbous end 14 will fit into the socket and will hold the vane 13 circumferentially in an accurate position. The direction of rotation of the impeller and the angular position of the vane is such that the reaction of the stock on the vane pulls on the vane against the holding strength of the insert 14.

The vane 13 is additionally held by being received in a slot 18 which extends angularly radially outwardly from the socket 15. The vane is planar having flat upper and lower surfaces and the slot 18 is of a size to snugly receive the vane as it is slid axially therein, and this holds the vane at its proper angle with respect to the rotor impeller 10.

To hold the vane seated in the socket and against the axial inner edge of the slot 18, a recessed head bolt 22 threads into the rotor impeller 10 into a block 20 welded in place and lying against the flange 10e of the rotor. The block 20 is threaded at 21 to receive the bolt 22. To additionally hold the vane in position, holes are drilled through its flat surface and a flattened land area 18a which is an extension of the slot 18 is drilled to receive bolts 23, 24 and 25 which are recessed and hold the vane in its position.

For removal of the vanes to refinish them or to insert new vanes, the bolts 23, 24 and 25 are removed, the bolt 22 is removed, and the vanes are slid axially out of the slot 18 and new or refinished vanes are readily replaced.

Thus, vanes of different characteristics can be readily substituted. Also, the horsepower drawn by the im-

steller may be changed by changing the shape or size of the vanes that are used. With the simple change the cost of rebuilding the impeller is very low and considerably reduced as contrasted with an impeller wherein the vanes are formed integrally. Further, damage to a single impeller vane edge can be taken care of by simply replacing the damaged vane without removal of the entire impeller as was heretofore necessary.

Thus, it will be seen that in operation the rotor rotates in a direction so that the vanes present a pulping surface and edge to the waste stock. The frictional pull on the vanes is against the locking socket arrangement so that the vanes are firmly and efficiently held. Wear which occurs will prevail on the facing flat surfaces and outer edges of the vanes so that by replacement of the vanes, a completely fresh pulping surface will be presented to the stock. Also, in different types of operation or in different horsepower requirements, vanes of different heights or different characters can be readily exchanged and replaced with a minimum of shutdown time for the impeller. Also, if a single vane is damaged, it is not necessary to remove the entire impeller as was heretofore necessary. Also, depending upon the position of the elements in the particular design of refiner used, individual vanes can be changed without necessitating completely draining the machine although this is not true in a vertical pulper. Also, in certain processes it may become desirable to use different vanes of different characteristics around the periphery of the impeller and this can be accomplished by using different vanes at different stations. Also, dynamic balancing of the impeller can be accomplished by the insertion of vanes of different weights. It will be appreciated that a recessed type of holding bolt is advantageous for locking the vanes in place, but that other types of specific types of fastening bolts may be employed.

Thus, it will be seen that I have provided an improved impeller construction which achieves the advantages and objectives set forth above, which is readily assembled and disassembled and provides for an improved construction which achieves improved refining operations.

I claim:

1. A construction for a paper pulper comprising, an impeller rotor having at least one blade receiving station for supporting the blade at the station, a blade for each of the stations being generally planar and having a shaped outer end with cutting edges, the inner end of the blade having an enlarged positioning portion, said rotor station having an accurately located socket for receiving said enlarged positioning portion of the blade so that the blade is radially and circumferentially supported against circumferential running forces and against impact forces due to engagement with the materials being refined, and

bolt means extending through said blade into the rotor for additionally holding the blade at a station where it is located by said positioning portion.

2. A construction for a paper pulper comprising, a rotor having a plurality of circumferentially spaced blade receiving stations for supporting a blade at each of the stations,

a plurality of generally planar blades for the stations each having shaped outer ends for cutting materials to be processed, the inner ends of each of the blades being bulbous with a thickness greater than the planar blade, axially opening the sockets in the rotor for receiving said bulbous ends and being accurately located to accurately position the blades,

additional securing means on the rotor for securing the blades, including narrow slots opening radially and opening axially in the same direction as the sockets for receiving the blades with these slots being of substantially the thickness of the blades to aid in holding them in position.

3. A construction for a paper pulper comprising, a rotor having a plurality of circumferentially spaced blade receiving stations for supporting a blade at each of the stations,

a plurality of generally planar blades for the stations each having shaped outer ends for cutting materials to be processed, the inner ends of each of the blades being bulbous with a thickness greater than the planar blade, axially opening the sockets in the rotor for receiving said bulbous ends and being accurately located to accurately position the blades, additional securing means on the rotor for securing the blades,

the bulbous ends of the blades having a center opening for receiving a bolt and the socket of the rotor having means for accommodating the fastening of the bolt.

4. A construction for a paper pulper in accordance with claim 2 including bolt openings through each of the blades with means in the rotor for receiving the bolts to additionally secure the blades.

5. A construction for a paper pulper comprising, a rotor having a plurality of circumferentially spaced blade receiving stations for supporting a blade at each of the stations,

a plurality of generally planar blades for the stations each having shaped outer ends for cutting materials to be processed, the inner ends of each of the blades being bulbous with a thickness greater than the planar blade, axially opening the sockets in the rotor for receiving said bulbous ends and being accurately located to accurately position the blades,

additional securing means on the rotor for securing the blades, the bulbous end of the blade having an axially extending opening for receiving a bolt, and

means on the rotor for securing the bolt, the blades each having angular circumferentially extending openings for bolts to extend into angular circumferential openings in the rotor for additionally securing the blades.

6. A construction for a paper pulper comprising, an impeller rotor having at least one blade receiving station for supporting the blade at the station, a blade for each of the stations being generally planar and having a shaped outer end with cutting edges, the inner end of the blade having an enlarged positioning portion, said rotor station having an accurately located socket for receiving said en-

larged positioning portion of the blade so that the blade is radially and circumferentially supported against circumferential running forces and against impact forces due to engagement with the materials being refined, the blade having planar upper and lower surfaces and the rotor having parallel planar supporting

surfaces which surfaces extend axially in a direction parallel to the axis of the rotor and which extend radially at a trailing angle so that the reaction of the blade with the material being refined pulls against said socket.
